BASKET MAKING MACHINE

Walter F. Newhouse, Benton Harbor, Mich.

Application November 18, 1935, Serial No. 50,277

9 Claims. (Cl. 147—47)

This invention relates to basket machinery, and more particularly to machinery for making the modern straight side bushel baskets, or half bushel baskets, by which is meant a basket made from a single mat of crossed staves of splint material with an arched bottom, and top and bottom and middle hoops, and with the bottom hoop secured in position to maintain the arched formation of the basket bottom, and the invention relates especially to the instrumentalities and method for securing the said bottom hoop in place.

Generally stated, the object of the invention is to provide an improved construction and method whereby the machine itself is provided with mechanical means for bending and shaping the staves over the corner or edge of the smaller end of the frusto-conical basket form upon which the baskets are made, and at the same time stapling the said bottom hoop in position with its lower edge flush, or practically flush, with the bottom of the basket, by coiling the bottom hoop strip over an element of the said mechanical means for bending and shaping the staves against the adjacent corner of the basket form, and by thereafter withdrawing the said machine element from between the bottom hoop and the side of the basket, leaving said hoop tightly fastened in place, and with the lower edge of the hoop flush, or practically flush, with the bottom of the basket.

It is also an object to provide certain details and features of construction and combinations tending to increase the general efficiency and the desirability of a basket-making machine of this particular character.

To the foregoing and other useful ends, the invention consists in matters hereinafter set forth and claimed and shown in the accompanying drawings, in which—

Fig. 1 is a side elevation of a basket machine embodying the principles of the invention.

Fig. 2 is a transverse section, on a different scale, on line 2—2 in Fig. 4 of the drawings.

Fig. 3 is a similar section on line 3—3 in Fig. 4 of the drawings.

Fig. 4 is an enlarged side elevation of the shaping and forming instrumentalities of the machine, showing the operation of making a basket thereon, with certain portions shown in longitudinal section to facilitate the illustration of the invention.

Fig. 5 is an enlarged fragmentary longitudinal sectional view, illustrating the step of shaping and forming the bottom structure of the basket.

Fig. 6 is a view similar to Fig. 5, showing the

bottom clamping plate withdrawn from engagement with the bottom of the basket.

Fig. 7 is a plan view of the mat from which the basket is made.

Fig. 8 is a perspective of one of the finished baskets, shown upside down.

Fig. 9 is a detailed sectional view showing the ratchet feed for intermittently rotating the tapered basket form.

Fig. 10 is a transverse section on line 10—10 in Fig. 9 of the drawings.

As thus illustrated, referring to Figs. 1 to 6 inclusive, the invention comprises a tapered basket form 1, mounted to rotate on the reduced end portion (see Fig. 9) of the longitudinal and horizontally extending bar 2, which latter may be reciprocated longitudinally of the machine by any suitable known or approved means.

Opposing the said basket form 1, is a bottom clamping plate 3, mounted to be rotated intermittently by the ratchet feed mechanism 4, which latter may be of any suitable known or approved character. A reciprocating ram or rod 5 extends longitudinally and centrally through the clamping plate 3, and through the means for intermittently rotating said plate, for the purpose of pushing or forcing the bottom of the basket into the recessed or concave face of the smaller end of the form 1, in order in effect to arch the basket bottom. Any suitable or desired means can be employed for operating the ram or rod 5, and for yieldingly pushing it against the bottom of the basket, so that when the form 1 is within the housing 6, which latter is rigidly secured to the body 7 of the machine, the said ram or rod 5 will then be in the position shown in Fig. 4 of the drawings. The bottom clamping plate 3 is formed with a gear 8, and within the housing a gear ring 9 is mounted to engage the sides of the basket between the top and bottom hoops thereof, as shown more clearly in Fig. 4 of the drawings.

Near the lower side of the housing, a counter shaft 10 is mounted, parallel with the axis of the rotary forming instrumentalities, and this counter shaft is provided with a pinion 11 for engaging the gear 8, and with another pinion 12 for engaging the gear ring 9, whereby the latter is rotated intermittently in unison with the bottom clamping plate 3, during the operation of stapling the top hoop 13, the middle hoop 14, and the bottom hoop 15, in place on the downwardly tapered sides of the basket.

The rotary form 1 may be rotated by its frictional engagement with the basket and by the pressure of the bottom clamping plate 3, and it

may also be rotated in unison with the bottom clamping plate by another ratchet device 16, splined on the integral sleeve or hub portion of the form 1, so that the form 1 and bar 2 may 5 reciprocate while the ratchet remains in the vertical plane thereof, as shown in Figs. 9 and 10 of the drawings, if so desired.

The three outside hoops of the basket are 10 stapled in place by the three staplers 17, 18 and 19, the latter stapling the bottom hoop 15 in place, and for this purpose the housing 6 has its upper side provided with slots or openings 20 and 21, through which the staple formers and drivers operate to insert the staples through the 15 hoops and through the staves of the basket.

For the purpose of shaping or forming the 20 staves over the corner 22 of the smaller end of the basket form 1, the bottom clamping plate 3 is provided with a ring 23 having a tapered flange 24 that extends a distance over the sides of the basket, during the operation of stapling the hoops in place, as shown in Fig. 5 of the drawings. This means, of course, that the flange 24 actually extends between the bottom hoop 15 and the sides 25 of the basket, whereby the lower corner formation of the basket is actually completed and fully formed before the bottom hoop is stapled in place, and it will be understood that these hoops are formed from strips, so-called hoop strips, that 30 are fed through the three hoop guides 25 to the adjacent upper side of the stave assembly, under the staplers, so that the latter may progressively staple the hoop strips in place on the sides of the basket, in the well known manner, except that 35 in this case there is a mechanical element, the tapered flange 24, which is between the bottom hoop 15 and the sides of the basket, during the operation of stapling this hoop in place. When the basket is finished, and the forming instrumentalities are separated, leaving the finished 40 basket on the form 1, the said flange 24 is withdrawn from between the hoop 15 and the sides of the basket, in the manner shown in Fig. 6 of the drawings, leaving the lower edge portion of the 45 hoop free to tightly hug the bottom end of the basket, and flush, or practically flush, with the bottom of the basket. Thus the staves 26, from which the mat shown in Fig. 7 is made, are fully shaped and formed, in the bottom construction of 50 the basket, and are tightly and fully bent over the bottom edge of the basket form, before the bottom hoop is secured in place, and hence the said bottom hoop does not serve to perform the function of making the final sharp bend in the staves, 55 over the corner of the basket form, with the construction and method shown and described. Of course, to some extent, before the bottom hoop is secured in place, the staves, at a point immediately beyond the edge of the flange 24, are not 60 tightly against the sides of the form, and it is the coiling and stapling of the bottom hoop 15 in place that causes them to conform to the curved sides of the basket form, when this hoop is stapled in place. In Fig. 7, the line 27 indicates approximately the points at which the 65 staves are bent, and it will be seen that with the annular flange 24, co-operating with the annular corner 22 of the form, the staves are actually bent along a curved line, transversely of the stave, as 70 distinguished from prior methods in which the bending or breaking of the stave was along a straight transverse line.

Obviously, with the bottom clamping plate 3 slightly bulged or crowned on its face 28, as 75 shown in Figs. 4 and 5, the bottom of the basket

will be more or less concave. However, as is well known, the bottom surface of the bottom wall of a basket of this kind can be perfectly flat, and at the same time have an arched or crowned upper surface to prevent sagging under the load. The 5 bottom hoop 15 functions, in the ultimate or finished basket, as a circumscribing restriction to maintain the said arched formation of the basket bottom.

It will be understood that the staplers and other 10 common or ordinary portions of the machine may be operated in any suitable known or approved manner, as these elements form no part of the invention. For example, the well known friction brake 29 may be employed in connection with the 15 bottom clamping plate 3, to prevent over-feeding by the ratchet mechanism 4, in the well known manner. In this way, therefore, with the mechanical instrumentalities shown and described, and the method disclosed, a bushel or half bushel 20 basket is produced, from a single mat of crossed staves of wood veneer, thin splint material, that has a nicely molded and rounded outer corner for the bottom of the basket, and that has a bottom hoop, the lower edge of which is flush with the 25 bottom of the basket, or practically so, the said nicely molded or formed corner for the basket being produced first, in the operation of making the basket, so that the said bottom hoop has nothing to do with the said formation of the 30 said bottom corner of the basket, when it is coiled and fastened in place, notwithstanding that the bottom hoop is not disposed a distance above the bottom of the basket, but is practically flush therewith, and in the practice of this method, it is 35 convenient and effective to interpose an annular mechanical element, a thin element, between the hoop and the sides of the basket, as shown and described, during the coiling and fastening of the bottom hoop in place, inasmuch as the hoop is 40 coiled around the periphery of said annular mechanical element, so that the latter must be withdrawn from between the hoop and the sides of the basket in the operation of removing the finished basket from the machine. 45

It will be understood that the staples 30, driven 50 through the bottom hoop 15 and the thin splint staves of the basket, are clinched on the sides of the basket form 1, and it will be seen that this is done while the ring 23 is holding the rounded bottom corner formation of the basket in the exact condition desired therefor in the ultimate basket. The flange 24 could be integral with the bottom clamping plate, but when formed on a 55 separate ring, such as the ring 23, it is obvious that this flange and the ring may be of hardened steel, while the plate 3 may be of less expensive metal, such as cast iron. This is desirable, in order to guard against breakage of the flange 24, as the latter is under the stapler 19, and the staple former and driver of the latter may exert some pressure on the flange, or may come rather close to it, and hence it is desirable that the flange be of tough steel or other material that will not be liable to be injured by the pounding of the 60 stapler. 65

Thus an annular forming element formed with an edge portion adapted to extend within the bottom hoop is essential to the invention.

What I claim as my invention is:

1. A machine for hooping a basket, comprising 70 means for supporting the basket and the hoop in position to be stapled together, and an annular member adapted to embrace the bottom of the basket and having a thin edge portion adapted 75

to extend a distance along the sides of the basket and being unobstructed outwardly thereof sufficiently to extend between the hoop and the basket body, to thereby shape and hold the body at points underlying the hoop while the hoop is being stapled.

2. A structure as specified in claim 1, said member being curved and rounded internally to shape the rounded bottom corner of the basket

10 where the downwardly tapering sides join the outer edge of the convex bottom of the basket.

3. A structure as specified in claim 1, said member being movably supported rotatable with the basket to progressively staple the hoop in

15 position adjacent the bottom corner of the basket.

4. A structure as specified in claim 1, comprising automatic means for causing the withdrawal of said edge from between the hoop and the basket body, after the completion of the stapling

20 of the hoop and body together.

5. A structure as specified in claim 1, comprising a bottom clamping plate for clamping and arching the bottom wall of the basket, rigid with said annular member.

25 6. A structure as specified in claim 1, comprising a bottom clamping plate for clamping and arching the bottom wall of the basket, rigid with

ing a bottom clamping plate for clamping and arching the bottom wall of the basket, rigid with said annular member, together with means for communicating power to said clamping plate to rotate the basket.

7. A structure as specified in claim 1, comprising means for communicating power to said supporting means, and to said annular member, to rotate the basket during the hooping operation.

8. A structure as specified in claim 1, said thin edge stopping short of the staples by which the hoop is secured to the basket, to prevent the staples from engaging said edge, while the latter is in tight engagement with the basket.

9. A machine for making containers, comprising an annular member having a thin edge for positioning between superposed portions of the container, to shape one portion at points underlying the other portion, and means for effecting a fastening of the portions together while said member is between the two portions, and means for withdrawing said member from between said portions of the container, after the fastening operation has been completed.

WALTER F. NEWHOUSE. 25
